Primary Examiner—Susan J. Lucas*Assistant Examiner*—Cynthia E. Ramirez*Attorney, Agent, or Firm*—Barry E. Deutsch[57] **CLAIM**

The ornamental design for a handle for an electric iron, as shown and described.

DESCRIPTION

FIG. 1 is a front, top and right side perspective view of a handle for an electric iron showing my new design;

FIG. 2 is a front elevational view thereof;

FIG. 3 is a top plan view thereof;

FIG. 4 is a right side elevational view thereof;

FIG. 5 is a rear elevational view thereof;

FIG. 6 is a bottom plan view thereof; and,

FIG. 7 is a left side elevational view thereof.

The broken line showing of an electric iron in the figures is for illustrative purposes only and forms no part of the claimed design.
